JOSEPH E. CASEY, OF PROVIDENCE, RHODE ISLAND, ASSIGNOR TO PROVIDENCE GAS BURNER COMPANY, OF PROVIDENCE, RHODE ISLAND.

INCANDESCENT-ELECTRIC-LAMP BASE.

SPECIFICATION forming part of Letters Patent No. 744,957, dated November 24, 1903.

Application filed July 20, 1903. Serial No. 166,391. (No model.)

To all whom it may concern:

Be it known that I, JOSEPH E. CASEY, a citizen of the United States, residing at Providence, in the county of Providence and State 5 of Rhode Island, have invented a new and useful Improvement in Incandescent-Electric-Lamp Bases, of which the following is a specification.

This invention has reference to an improvement in incandescent-electric-lamp bases, and more particularly to an improvement in the contact-plate of the base connecting the lamp with the lamp-socket.

In incandescent-lamp bases as heretofore 15 constructed the contact-plate on the porcelain insulating-cap forming the end of the base was secured to the cap by a tubular rivet forming a part of the contact-plate. This rivet extends centrally from the contact-plate 20 through a central hole in the cap and is upset on the end, securing the contact-plate to the cap. One of the connecting-wires from the lamp passes through the tubular rivet of the contact-plate and is soldered to the contact-plate. The other wire passes through a 25 hole in the insulating-cap and is soldered to the shell of the base. In this construction the frictional resistance on the contact-plate in screwing the lamp into its socket is liable 30 to turn the contact-plate on the cap and break the wire connection to the lamp.

The object of my invention is to prevent the turning of the contact-plate on the insulating-cap forming the end of the base of an 35 incandescent lamp and the breaking of the connecting-wire from the lamp to the contact-plate.

My invention consists in the peculiar and novel construction of the base of an incandescent electric lamp, whereby the contact-plate on the end of the base is prevented 40 from turning and breaking the connecting-wire from the lamp to the contact-plate, as will be more fully set forth hereinafter.

Figure 1 is a side view of my improved incandescent-electric-lamp base, showing the lamp in broken lines. Fig. 2 is an enlarged end view of the base, showing the means for preventing the contact-plate from turning, 45 consisting of a rib on the contact-plate extending into a groove in the insulating-cap.

forming the end of the base. Fig. 3 is an enlarged sectional view of the base, taken on line X X of Fig. 1, showing the rib on the contact-plate in the groove in the insulating-cap and the central tubular rivet securing the contact-plate to the insulating-cap. Fig. 4 is an end view of the insulating-cap, showing the groove for the rib on the contact-plate. Fig. 5 is a view looking at the under 55 side of the contact-plate, showing the rib and tubular rivet; and Fig. 6 is an edge view of the contact-plate, showing the stamped rib on the plate and the tubular rivet formed in one piece with the plate.

In the drawings, *a* indicates the usual shell of an incandescent-electric-lamp base, *b* the porcelain insulating-cap, and *c* the contact-plate. The shell *a* has the usual screw-thread *a'* and the contracted end *a''* for securing the 70 insulating-cap *b* to the shell by spinning the end over the edge of the insulating-cap. The insulating-cap *b* has the central hole *b'*, the V-shaped groove *b''*, crossing the central hole, the hole *b'''* for the wire connection from the 75 lamp, and the indentures *b''''* in the under edge of the cap to prevent the cap from turning in the contracted end *a''* by forcing the metal of the contracted end into the indentures *b''''* in the cap. The contact-plate *c* 80 has the tubular rivet *c'*, formed from the plate and the stamped rib *c''*, on the under side of the plate. The contact-plate *c* is secured on the insulating-cap *b* by the tubular rivet *c'* in the hole *b'* and is prevented from turning 85 on the insulating-cap by the rib *c''* on the plate coinciding with the groove *b''* in the insulating-cap.

One of the connecting-wires from the lamp is carried through the tubular rivet *c'* and 90 soldered in the groove formed by the stamped rib *c''* on the contact-plate and the other carried through the hole *b'''* in the insulating-cap *b* and soldered to the shell *a* of the base.

By the use of my improved base for incandescent electric lamps the contact-plate is prevented from turning and breaking the connecting-wire from the lamp, and a more perfect and durable incandescent-electric-lamp base is constructed than has heretofore 95 been done.

It is evident that points bent downward

from the edge of the contact-plate to enter the groove or indentures in the insulating-cap could be used without materially affecting the spirit of my invention.

5 Having thus described my invention, I claim as new and desire to secure by Letters Patent—

In a base for incandescent lamps, a screw-threaded cylindrical shell, an insulating-cap secured in one end of the shell, means for securing the contact-plate to the insulating-cap, and means for preventing the contact-

plate from turning on the cap, consisting of a rib on the plate coinciding with a groove in the insulating-cap, for the purpose as described.

In testimony whereof I have signed my name to this specification in the presence of two subscribing witnesses.

JOSEPH E. CASEY.
